UNITED STATES PATENT OFFICE.

JOSEPH E. FAWELL, OF PITTSBURGH, PENNSYLVANIA.

ROLLING-MILL.

1,192,814.

Specification of Letters Patent. Patented July 25, 1916.

Application filed January 30, 1915, Serial No. 5,316. Renewed May 29, 1916. Serial No. 100,705.

To all whom it may concern:

Be it known that I, JOSEPH EDWARD FAWELL, residing at Pittsburgh, in the county of Allegheny and State of Pennsylvania, a citizen of the United States, have invented or discovered certain new and useful Improvements in Rolling-Mills, of which improvements the following is a specification.

10 In Letters Patent granted March 9th, 1915, and numbered 1,131,604, and in an application filed January 30th 1915, Serial No. 5315 are shown and described certain embodiments of a new type of rolling mill in which 15 two pairs or sets of rolls are movable in a vertical plane to and from operative position, one pair of rolls being driven to move the article while reducing it, in one direction, and the other pair being driven to effect, 20 feet an opposite movement of the article.

The invention described herein relates to certain improvements whereby the pass dimensions of the pairs of rolls may be increased or decreased as required and also to 25 certain improvements in the manner of operating said pairs of rolls.

In the accompanying drawings forming a part of this specification, Figure 1 is a top plane view of the improved mill; Fig. 2 is a 30 side elevation of the same; Fig. 3 is a sectional elevation on a plane indicated by the line III—III Fig. 2, and Fig. 4 is an end elevation of the pinion housing; Fig. 5 is a 35 sectional view illustrating a modification of the supports intermediate of the pairs of rolls; Fig. 6 is a section on a plane indicated by the line VI—VI, Fig. 5, and Fig. 7 is a detail view.

As in the construction shown and described in the application Serial No. 5315 filed of even date herewith, the lower ends 40 of housings 4 are formed on arcs of circles and rest upon rollers 42 mounted in the bed of the mill. While any suitable means may 45 be employed to rock the housings on the rollers, it is preferred to employ single acting fluid pressure cylinders 53 and 54 for that purpose. The cylinders are oppositely arranged and have their pistons or rams 50 connected to cross-heads 49 and 50 which in turn are connected by pitmen 47 and 48 to the housings, as fully described and shown in said application. The movements of the 55 housings are limited by stops 55 and 56 on the housings encountering abutments 57 and 58 on the bed of the mill, and in order to

prevent injurious shocks or jars, the final movements of the housings are arrested by cushioning devices preferably consisting of air cylinders.

In the form of mill shown in Patent No. 1,131,604 windows of housings which are adapted to receive the bearings for the journals of the rolls are arranged at such an angle relative one to the other, that when 65 one pair of rolls are in working position, a horizontal plane tangential to the top of the lower roll of the working pair will pass over and be tangential to the upper roll of the other or non-working pair, and this upper 70 roll is employed to feed the article along. It will be readily understood that the employment of the upper rolls to feed the article is practicable only in cases where the positions of the upper rolls are fixed or 75 said rolls are adjustable only to compensate for wear.

In mills where provision must be made for substantially changing the pass dimensions by shifting the upper rolls from and toward 80 the lower rolls, the windows for one pair of rolls should be at such an angle to those for the other pair, that when one pair of rolls is in working position, the top roll of the other or non-working pair will even when shifted to 85 the maximum distance from its lower roll, be substantially below a horizontal plane tangential to the top of the lower roll of the pair in working position as shown in Fig. 3. When the mill is in the position shown in 90 the drawings the rolls c—d are in working position, and in order to carry the article from the feed table B to these rolls, support 80^a is arranged in front of or on the feed 95 side of these rolls, said support being preferably in the form of a roller having its journals mounted in suitable bearings on the housings. A similar support 80^b is arranged in front of the other pair of rolls a b. In order to carry the article from the 100 rolls c—d to the feed table A, two supports 81^b preferably in the form of rollers are so arranged in the rear of rolls c—d that their upper surfaces will be tangential or approximately tangential to a horizontal plane 105 which is tangential to the top of the lower roll d. In line with these rollers 81^b is arranged a bridge 82^b which will carry the piece over the upper roll a and onto the table A. Similar supports 81^a and a bridge 110 82^a are provided for carrying the article from the rolls a b, when in operative posi-

tion, over the roll *c* and onto the table B. As the rollers 81^b and 81^a are spaced a considerable distance apart, it is preferred to employ an intermediate support 83.

5 As the pieces to be rolled may be shorter than the distance between the working rolls and their receiving table, provision is made as clearly shown in Fig. 3 for driving the rollers for carrying the articles from the feed 10 table to the rolls and from the latter to the receiving table. It will be understood that the rollers 80^b and 81^b are driven in the same direction as the lower roll *d* while the rollers 80^a and 81^a are driven in the direction of the lower roll *b*.

In lieu of employing two sets of rollers intermediate the pair of rolls, two or more feed rollers 84, reversible but non-shiftable with the rolls, can be arranged intermediate 20 of the latter as shown in Figs. 5 and 6, these rollers having their journals mounted in the side pieces 85 connected by cross-bars 86, and provided with trunnions 87 and 88. The trunnion 87 is made circular in cross- 25 section and extends into a bearing in one of the housings, but the other trunnion 88 extends through the other housing and has its outer end secured in an anchor 89. As the axes of the trunnions coincide with the axis 30 of movement of the housings and as one of the trunnions is held stationary by the anchor the housing can be shifted without affecting the position of these intermediate supports.

35 As the feed tables A and B are vertically stationary and have their rollers tangential to a common horizontal plane, the rollers 84 are so mounted in the side pieces as to be tangential to the same plane, which passes 40 between the rolls of each pair when in working position. Provision is made for rotating one or more of the intermediate feed rollers by extending the journal of one of the rollers through the trunnion 88 and securing a bevel 45 pinion 91 on this extension 90. This pinion is driven by a corresponding pinion on a shaft 92, which can be connected with the mechanism employed for operating the rollers of tables A and B, so as to be driven 50 in the same direction as said rollers and to be reversible with the latter.

As the pairs of rolls do not in any sense form a continuous train, they may be driven independently one of the other and at different 55 rates, but it is preferred to drive them from a common motor through suitable housings as shown in Figs. 1, 2 and 4. The rolls of each pair are connected by universal 60 couplings 16 to one end of driving spindles or coupling shafts 17 which have their opposite ends similarly connected to the journals of pinions 18, 18^a and 19, 19^a. The pinions of each pair intermesh so that the rolls driven thereby will rotate in opposite directions and the shafts carrying respectively

one pinion of each pair (the upper pinions in the construction shown) are extended and have secured thereon gear wheels 20 which intermesh so that the rolls of one pair will rotate in a reverse direction to those of the other pair. One of the gear wheels 20 is operatively connected to the motor shaft.

In the type of mill shown herein provision is made for varying the relative positions of the rolls of each pair by means of screws passing through the caps 69 of the windows in which the roll journals are mounted. As it is preferred that the screws for each pair should be shifted simultaneously, the nuts 93 engaging the screws are 80 provided with worm wheels 94, which are engaged by worms on the shafts 95 arranged parallel with the rolls as shown in Figs. 1 and 2. It is preferred that the shafts 95 should be driven by independent motors 96 85 which may be of any suitable construction. The upper rolls may be held in operative relation to the shifting screws by any of the means known in the art, as for example in the manner shown in Fig. 5, the screws having a swivel connection with the upper bearing blocks 97 for the journals of the rolls and the lower blocks or saddles as they are usually termed being bolted to the upper blocks.

90 I claim herein as my invention:

1. In a rolling mill, the combination of two sets of rolls, means for shifting said sets of rolls alternately to and from working position, and means intermediate said sets of 100 rolls for moving the article being reduced from the rolls in working position.

2. In a rolling mill, the combination of two sets of rolls, means for shifting said sets of rolls alternately to and from working position, and means for carrying the article being reduced from the rolls in working position over the rolls in inoperative or non-working position.

3. In a rolling mill, the combination of 110 two sets of rolls, means for rotating said sets of rolls in opposite directions, respectively, and reversible means intermediate the sets of rolls for carrying the article from the set of rolls in working position, and means for 115 shifting said sets of rolls alternately to and from working position.

4. In a rolling mill, the combination of two main feed tables, spaced a suitable distance apart, a feed table intermediate the 120 main tables, the several tables being provided with reversible feed rollers, two sets of rolls, means for rotating said sets of rolls in opposite directions, respectively, and means for shifting said sets of rolls alternately, one set between a main table and the intermediate table and the other set between the intermediate and the other main table.

5. In a rolling mill, the combination of two sets of rolls, the axes of one set being

in a plane at an angle to a plane coincident with the axes of the other set, means for shifting said sets of rolls alternately to working position, two sets of pinions having universal driving connections with the respective rolls, the members of each set of pinions having their axes in a plane approximately coincident with a plane passing through the axes of the rolls driven by the

pinions when said rolls are in working position.

In testimony whereof, I have hereunto set my hand.

JOSEPH E. FAWELL.
